STOP MOTION FOR TWISTERS

Thomas M. Ripley, Aberdeen, Carson P. Ellis,
Pinehurst, and Frank G. Powers, Aberdeen,
N. C., assignors to Robbins Mills, Inc., New
York, N. Y., a corporation of New York

Application July 23, 1951, Serial No. 238,098

5 Claims. (Cl. 57—84)

1

This invention relates to yarn processing machinery and more especially to an improved stop motion for yarn twisting machines and the like.

It is well known to those familiar with the art that a twister frame or machine has a creel with yarn packages thereon from which strands of yarn pass downwardly and, in some instances, each of the strands of yarn passes over and around a top roll which normally rests upon a driven bottom roll, and then the yarn passes between the top and bottom rolls and half around the bottom roll after which the yarn passes through a corresponding yarn guide. The yarn then passes through the usual traveler mounted on a twister ring for directing the twisted yarn onto a bobbin or spool.

The twist is effected in the yarn by virtue of the movement of the traveler around the bobbin in directing the yarn thereto and it sometimes happens that the twist does not extend all the way along the strand from the traveler up to the rolls with the result that the yarn is easily broken between the rolls and the traveler or the strand of yarn may become parted due to various other reasons well known to those familiar with the art.

Heretofore, upon parting of the yarn, the top roll would continue to rotate in engagement with the bottom roll, because of the bottom roll being constantly driven. In so doing, the top roll would take up the yarn from the creel and it often happened that a substantial number of turns of yarn were wound about the top roll before the parted end of the yarn was discovered by an operator with the result that the turns of yarn wound about the top roll would have to be removed therefrom and discarded or the broken end would become entangled in nearby ends passing between adjacent rolls thus causing additional loss of yarn. It is evident that this not only required considerable time on the part of the operator but also resulted in a considerable amount of waste thereby relatively increasing the cost of the twisted yarn.

It is, therefore, a primary object of this invention to provide means operable automatically upon the yarn being parted for elevating the top roll out of engagement with the bottom roll thus preventing further rotation thereof although the bottom roll continues to rotate.

More specifically, it is an object of this invention to provide a pivoted roll lifter support, for each of the top rolls, which has a yarn guide thereon and a wedge-shaped roll separating or lifting member oscillatably mounted thereon, the sharp edge of the lifting member normally being

2

spaced closely adjacent the bite of the rolls. After the yarn passes beneath the bottom roll, it extends through the yarn guide extending from the roll lifter support and then downwardly through the traveler to the bobbin whereby the tension in the yarn serves to hold the roll separating member out of engagement with the rolls. On the other hand, upon undue slack occurring in the portion of the yarn extending between the rolls and the traveler or upon the strand being parted in this zone, the sharp end of the roll separating member frictionally engages the top and bottom rolls at the bite thereof and, due to the peripheral surfaces of the rolls moving in a direction away from the roll lifter support, the roll separating member will be pulled between the bite of the rolls and will thus raise the top roll out of engagement with the bottom roll.

It is another object of this invention to provide a twister stop motion of the type described with a shaft on which the top roll lifter supports are pivotally mounted in off-center relation so the center of gravity of each of the top roll lifter supports is disposed between the shaft and the bottom roll and to provide traverse limiting means fixed on the shaft for limiting pivotal movement of each top roll lifter support. This traverse limiting means is so arranged as to prevent inward movement of the roll separating member upon the yarn being parted and also limits outward movement of the roll lifter support so the top roll lifting or separating member is held in a semi-operative position closely adjacent the bite of the top and bottom rolls as the yarn, under tension, passes through the yarn guide on the roll lifter support.

It is still another object of this invention to provide a shaft locking mechanism or clutch mechanism for the shaft on which the roll lifter supports are pivotally mounted and to further provide an outturned handle on at least one end of said shaft for manipulation by an operator. The shaft locking or clutch mechanism includes a bearing member fixed to the frame of the twister or to one of its roll stands in which the shaft is oscillatably mounted and the bearing member is provided with at least one spring loaded detent therein. A collar is fixed on the shaft adjacent the bearing member and is provided with a pair of circularly spaced openings or cavities therein which are so positioned that the detent will engage one of the openings when the shaft is moved in one direction by the operator to lock the shaft in a first position. When the shaft is locked in this position, the means on

the shaft for limiting inward and outward movement of each of the roll lifter supports will permit the support to assume a semi-operative position as heretofore described so as to move inwardly between the top and bottom rolls upon the strand being parted.

Upon movement of the shaft in the opposite direction, to move the detent into engagement with the other of the cavities in the collar heretofore described, the traverse limiting means will cause the roll lifter support to move outwardly to prevent the free end of the top roll lifting or separating member from engaging either of the rolls although the strand of yarn may be unduly slack, or broken. This latter feature is particularly provided to facilitate the tying of the ends together or starting up after doffing and taking up the slack therein manually although the slack in the yarn may be such as to normally permit the roll separating member to engage the rolls and to thus be pulled inwardly to separate the top and bottom rolls.

Some of the objects of the invention having been stated, other objects will appear as the description proceeds when taken in connection with the accompanying drawings, in which—

Figure 1 is an enlarged fragmentary elevation with parts broken away and other parts being omitted and showing a portion of the creel, the top and bottom rolls, the yarn guide and the upper ends of bobbins in a portion of a ring rail and also showing the improved stop motion mounted on the rolls stands which support the top and bottom rolls;

Figure 2 is a schematic view, with parts in section, taken substantially along line 2—2 in Figure 1 and showing the first or original form of the invention in association therewith;

Figure 3 is a partially exploded isometric view showing how the shaft which supports the improved stop motion is mounted and showing the clutch or locking means therefor;

Figure 4 is an enlarged fragmentary elevation of the improved stop motion associated with the top and bottom rolls and the roll stands and being an enlarged elevation of the central left-hand portion of Figure 1;

Figure 5 is a fragmentary elevation, with parts in section, looking substantially at the right-hand side of Figure 4 and showing the improved stop motion in a partially or semi-operative position, such position being maintained during normal operation of the twister machine;

Figure 6 is a fragmentary vertical sectional view taken substantially along the line 6—6 in Figure 4 but showing the improved stop motion in a fully operative position as result of the strand of yarn being separated and, in which instance, the roll separating or lifting member is holding the top roll out of engagement with the bottom roll;

Figure 7 is an enlarged vertical sectional view taken substantially along line 7—7 in Figure 4 and showing a part of the shaft locking means or clutch;

Figure 8 is a fragmentary elevation similar to Figure 4 but showing a slightly modified second form of stop motion which is particularly adapted for use when the yarn passes beneath and half around the bottom roll, then passes around the top roll and extends downwardly from the top roll to the usual traveler;

Figure 9 is an elevation looking substantially at the right-hand side of Figure 8 and showing the

roll separating member or lifter in a partially or semi-operative position;

Figure 10 is a vertical sectional view taken substantially along the line 10—10 in Figure 8 but showing the roll separating or lifting member in a fully operative position, which occurs upon the yarn being broken or unduly slack;

Figure 11 is a third form of the invention which is quite similar to the original form of the invention, the top roll lifting member merely being shaped differently to accommodate a top roll of substantially smaller diameter than the bottom roll.

Referring more specifically to the drawings, the numeral 10 broadly designates the frame of a twisting machine comprising a roll stand support or girt 11, a creel 12 and an upper yarn guide support 13 which extend substantially the entire length of the machine. The machine also has a bolster rail, not shown, on which suitable spindles, not shown, are mounted for supporting bobbins or spools S or other suitable yarn take-up means. These spools or bobbins S extend through a ring rail 15, only a portion of which is shown in Figure 1, and which has suitable twister rings 16 fixed thereon through which the bobbins or spools S also extend.

The twister ring 16 may be of any desired construction and is shown in Figure 1 as having a conventional traveler 17 mounted for rotation thereon for directing yarn Y to the bobbin or spool S and for effecting twist in the yarn Y while maintaining tension in the yarn. As is well known to those familiar with the art, the ring rail 15 reciprocates in a vertical manner in the course of directing the yarn to the bobbin or spool S.

The creel 12 has a plurality of spindles 20 thereon on each of which a yarn package 21 is rotatably mounted and from which a strand of yarn Y-1 extends downwardly. It is evident that there may be other packages of yarn disposed in a higher plane than those shown in Figures 1 and 2 for directing one or more strands of yarn Y-2 downwardly to join the strand of yarn Y-1 to form the multi-ply strand Y which is subsequently twisted.

The yarn Y extends past and in engagement with a lease bar or rod 23 and then through a yarn guide 24 projecting from the upper yarn guide support 13. The yarn then passes beneath a shaft 25 and then upwardly over a rod 26 from whence the yarn extends forwardly, in one instance, and over the top surface of a top roll 27, which is of usual construction and which normally rests in engagement with a bottom roll 30 usually of lesser diameter than the top roll 27. The bottom roll 30 usually has a plurality of top rolls 27 resting thereon in end-to-end relation to each other as shown in Figure 1.

The bottom roll has reduced portions or may be fixed on a shaft 31 which is mounted for rotation in spaced roll stands 32 suitably secured to the upper surface of the roll stand support or girt 11. Each of the roll stands 32 is usually provided with a U-shaped notch or cavity 33 in which the shaft 31 of the bottom roll 30 is rotatably mounted, and which cavity 33 defines a front portion 34 which is utilized in supporting the bearing blocks of the improved stop motion to be later described.

The top rolls 27 are usually of a type having reduced end portions 35 integral therewith. There is disposed rearwardly of the top rolls 27 a horizontally disposed bar 36 having a plurality

of forwardly extending arms 37 thereon, there being one of these arms 37 disposed between the proximate ends of adjacent top rolls 27. The opposed sides of each of the forwardly projecting arms 37 are provided with vertically extending grooves 40 in which the reduced end portions 35 of the top rolls 27 are loosely mounted for rotational and vertical sliding movement therein. Each of the roll stands 32 is provided with a bifurcated upwardly projecting portion 41 for supporting the horizontally disposed bar 36.

Now, the yarn Y extends over the upper surface of each of the top rolls 27 and, in this instance, the yarn extends half way around the top roll 27, or may circumscribe the roll one or more times, and then passes between the top and bottom rolls 27 and 30 and substantially half way around the bottom roll 30. The yarn Y then extends forwardly through a yarn guide, to be presently described, and then downwardly through a lower yarn guide 43 which is pivoted, as at 44, on a bar 45. The bar 45 is suitably secured to brackets 46 which are, in turn, suitably secured to a common horizontally disposed bar 47 which is usually mounted for vertical movement on the horizontally disposed girt 11 of the frame 10. The yarn then extends downwardly through the traveler 17 as heretofore described.

The bottom roll 30 is driven by conventional means, not shown, to rotate in a counter-clockwise direction in Figure 2 or in a clockwise direction in Figures 5 and 6. Since the means for driving the bottom roll 30 is well known to those familiar with the art, an illustration and description thereof is deemed unnecessary. The bottom roll 30 is driven in timed relation to the speed in which rotation is imparted to the bobbins or spools S, the bobbins or spools S also being driven by conventional means, not shown.

The parts heretofore described are usual parts of a twisting machine and it is with these parts that the present invention is adapted to be associated. It is to be understood that the various parts of the twisting machine heretofore described may vary from that shown in the drawings and the present invention may be used in association with any type of yarn processing machine wherein the top roll rests upon the bottom rolls and rotate through contact therewith.

Now, as heretofore stated, the object of the invention is to provide an improved stop motion which will operate automatically upon the yarn Y being parted between the bite of the top and bottom rolls 27 and 30 and the corresponding spool or bobbin S to cause cessation of rotation of the top roll 27 and to thereby prevent the yarn from being wound several times about the top roll 27 before the parted yarn is discovered by an operator.

To this end, the improved stop motion comprises a wedge-shaped, beak-shaped or triangularly-shaped roll separator member or top roll lifting member broadly designated at 50, disposed adjacent each of the top rolls 27, and which is provided with forwardly or outwardly diverging upper and lower arcuate surfaces 51 and 52 which may conform substantially to the configuration of the peripheries of the rolls 27 and 30 at the bite thereof. This top roll lifting member 50 is preferably made from a friction material, such as leather and the like, to thereby insure that the bottom roll 30 will pull the top roll lifting member rearwardly or inwardly upon the rear or sharp end of the top roll lifting member 50 being moved into engagement with the top and bottom

rolls 27 and 30 at the juncture thereof in a manner to be later described.

The roll separating member or top roll lifting member 50 is provided with a front abutting surface 53 and has a forwardly projecting portion 54 at the upper edge thereof which is provided for pivotally supporting the top roll lifting member 50, as at 55, in the bifurcated upper end of an arm 56 which is an integral part of a roll lifter support or roll separator support broadly designated at 57. The arm 56 extends downwardly and has an enlarged or rearwardly projecting overbalancing portion 60 integral therewith, which is shown as being substantially circular in cross-section in Figure 6. This portion 60 is pivotally mounted on a shaft 61 which is spaced from the front surface of the bottom roll 30 and is preferably disposed in the same horizontal plane as the axis of the bottom roll 30.

It will be noted that the enlarged portion 60 of the roll lifter support 57 is eccentrically mounted on the shaft 61 with the greater portion of the enlarged portion 60 being disposed rearwardly of the shaft 61 or between the shaft 61 and the bottom roll 30. It will also be noted that when the arm 56 of the roll lifter support 57 is in the substantially vertical position shown in Figure 5, the free or rear end of the top roll lifting member 50 is spaced closely adjacent the bite of the top and bottom rolls 27 and 30 and the abutting surface 53 then engages the rear surface of the arm 56 due to the overbalanced manner in which the top roll lifting member 50 is mounted. This insures that the free or rear end of the top roll lifting member 50 is spaced from both the top and the bottom rolls while being disposed closely adjacent the juncture or bite of the rolls 27 and 30.

The enlarged portion 60 of the roll lifter support 57 has the shank 62 of a suitable yarn guide broadly designated at 63 adjustably secured therein as by a set screw 64. The shank 62 of the yarn guide extends downwardly and outwardly at an angle relative to the bottom roll 30 and is preferably provided with an elongated transversely extending loop portion 65. In this instance, the yarn passes half around the bottom roll 30 and then extends forwardly through the loop 65 of the yarn guide 63 from whence the yarn Y extends downwardly through the yarn guide 43 and the traveler 17, successively, to be wound about the spool S. Thus, when there is sufficient tension in the yarn Y, the yarn tends to urge the roll lifter support 57 in a counter-clockwise direction in Figures 5 and 6 thus holding the free end of the top roll lifting member 50 in spaced relation to the bite of the top and bottom rolls 27 and 30. Conventional means, not shown, are usually provided on twisters and the like to cause the yarn to traverse each of the top rolls 27 longitudinally thereof to prevent the yarn from wearing grooves in the peripheries of the top and bottom rolls. Therefore, the inner or rear edge of the top roll lifting member 50 is normally spaced from the bite of the top and bottom rolls 27 and 30 sufficiently to permit the yarn to pass about the rolls 27 and 30 without engaging the top roll lifting member 50 during the traversing of the yarn. This is also the reason for providing the transverse elongation of the loop portion 65 on the yarn guide 63. The yarn Y usually passes around the top rolls 27 a number of times before it passes half around the bottom roll 30. However, the yarn is shown as passing only half around the top rolls 27 for purposes of clarity. In order to limit movement of the roll lifter sup-

port 57 in opposite directions about the shaft 61, the roll lifter support 57 has a cavity 66 in the front surface thereof which is loosely penetrated by the shaft 61. The shaft 61 has a traverse limiting member or cam 67 adjustably secured thereon as by a set screw 73. This traverse limiting member 67 is disposed within the cavity 66 in the enlarged portion 60 of the roll lifter support 57 and is slightly smaller than the cavity 66 so as to permit oscillation of the roll lifter support 57 about the shaft 61.

However, the upper and lower surfaces of the traverse limiting member 67 are disposed relative to the upper and lower walls of the cavity 66 so that the upper wall of the cavity 66 engages the upper surface of the traverse limiting member 67 upon normal tension in the yarn Y causing the roll lifter support 57 to be urged in a counter-clockwise direction in Figure 5. Now, upon the yarn Y being parted at a point anywhere along the portion of its length extending between the bite of the top and bottom rolls 27 and 30, respectively, and the traveler 17, the weight of the enlarged portion 60 of the roll lifter support 57 combined with the weight of the top roll lifting member 50 urges the top roll lifting member 50 rearwardly or in a clockwise direction from the position shown in Figure 5 to substantially the position shown in Figure 6, or until the free end of the top roll lifting member 50 is in tight enough engagement with the bottom roll 30 to cause the bottom roll 30 to pull the top roll lifting member 50 rearwardly and to lift the top roll out of engagement with the bottom roll 30. It is evident that the top roll lifting member 50 is pivoted at 55 so the sharp or rear edge of the same may move rearwardly in a substantially straight line, although the pivot point 55 moves downwardly in an arcuate path as it moves rearwardly. The inward or rearward movement of the top roll lifting member 50 is limited by the bottom wall of the cavity 66 engaging the lower surface of the traverse limiting member 67. Although the stop motion devices, comprising the top roll lifting members 50 and the supports 57, are shown to one side of the centers of the top rolls 27 in Figure 1, the position of each device is determined by the center of gravity of the corresponding top roll since it is evident that the top roll must be balanced on the top roll lifting member 50 in order to prevent one of the ends of the top roll from engaging the bottom roll after the yarn is parted. Otherwise, the top roll would continue to rotate and would defeat the purpose of the stop motion devices.

The shaft 61 is oscillatably mounted in bearing blocks 72 and 73 suitably secured adjacent the outer or front surfaces of the portions 34 of the spaced roll stands 32. In this instance, each of the bearing blocks 72 and 73 has a slotted rearwardly extending projection 70 at the upper end thereof which is suitably secured, as by a screw 75, to the upper surface of the portion 34 of the corresponding roll stand 32. The bearing block 72 differs from the bearing block 73, since this bearing block 72 serves as a primary element of a clutch or shaft locking means which will now be described. The shaft 61 is prevented from moving from left to right in Figures 1 and 4 by a suitable collar 76 which is adjustably secured as the shaft 61 by a set screw 77 and which slidably and rotatably engages the left-hand surface of the bearing block 72 in Figures 1 and 4. This collar 76 is shown in exploded rela-

tion to the bearing block 72 in Figure 3 for purposes of clarity.

The collar 76 also serves to hold a clutch member or collar 80 in sliding rotational engagement with the opposite surface of the bearing block 72 from that which is engaged by the collar 76. The clutch member 80 has a recess 81 cut in its periphery and into which a traverse limiting pin 82 projects from the proximate surface of the bearing block 72. The purpose of this traverse limiting pin 82 is to limit oscillatory movement of the shaft 61, on which the collar or clutch member 80 is adjustably secured, as by a set screw 83. The pin 82 is suitably secured in the bearing block 72 as by a pressed fit.

In order to lock the shaft 61 in the desired position, for purposes to be presently described, the bearing block 72 has a cavity or bore 84 in its right-hand surface in Figures 1 and 4, in which a spring loaded detent 85 is slidably mounted. This spring loaded detent 85 is normally urged outwardly with respect to the bearing block 72 by a compression spring 86 disposed within the bore or cavity 84. The spring loaded detent 85 is preferably disposed in diametrically opposed relation to the pin 82 relative to the shaft 61.

The collar or clutch member 80 is provided with a pair of indentations or cavities 90 and 91 which are preferably bridged by a shallow passageway or cavity 92 of less depth than the cavities 90 and 91. This recess 92 is provided because of the outer end of the detent 85 being rounded and to assist in leading the detent 85 out of the cavities 90 and 91, the detent 85 being urged into the corresponding cavity 90 or 91 depending upon the position of the shaft 61. The outer or left-hand end of the shaft 61 is provided with a handle portion 93 which may be manipulated by an operator for shifting the position of the shaft 61 for aligning the desired cavity 90 or 91 with the detent 85.

Now, the purpose of the clutch or locking mechanism heretofore described is to provide means for holding the rear ends of the top roll lifting members 50 out of engagement with corresponding top rolls 27 and bottom rolls 30 although the yarn Y may be parted. This may be required in tying several ends of yarn in rapid succession, such as in setting up the machine, or it may happen that considerable slack is effected in the portion of yarn extending between the bite of the top and bottom rolls 27 and 30 and the traveler 17 after the ends of the yarn have been tied together. This would require that the yarn be pulled in a reverse direction or upwardly between the rolls 27 and 30 by an operator to take up the slack in the yarn and during which it may be desirable that the top roll 27 rests in engagement with the bottom roll 30.

Therefore, when an operator desires to move all of the stop motion units, comprising the top roll lifter support 57 and the top roll lifting member 50, to a fully inoperative position, the operator merely moves the handle 93 downwardly in order to move the shaft 61 in a counter-clockwise direction beyond the position shown in Figure 5. The cavity 91 will then register with the detent 85 and the spring 86 will cause the detent 85 to enter the cavity 91 thus holding the shaft 61 in the desired position so the lower surface of the traverse limiting member 67 engages the bottom wall of the cavity 66 to thus prevent rearward movement of the top roll lifting member 30, although the yarn Y may be unduly slack

or parted. The pin 82 engages the corresponding wall of the cavity or recess 81 in the collar 80 to insure that the shaft 61 is not rotating to where the detent 85 would be disposed beyond the edge of the cavity 91 relative to the cavity 90.

It is evident that, upon the operator subsequently rotating the shaft 61 in a clockwise direction in Figure 6, the detent 85 then registers with the cavity 90 to lock the shaft 61 so the roll lifter support 57 and the top roll lifting member 50 assume a semi-operative position as the yarn Y passes through the yarn guide 63 under proper tension.

Second form of stop motion device

The second form of stop motion device is shown in Figures 8, 9 and 10. This form of stop motion device differs only slightly from the original form of stop motion device and, therefore, the parts of the second form of stop motion device will bear the same reference characters as corresponding parts of the original form of stop motion device with the letter "a" affixed thereto in order to avoid repetitive description.

The form of stop motion device shown in Figures 8, 9, and 10 is particularly provided for use on twisting machines and the like wherein yarn Y—a is initially directed beneath the bottom roll 30a instead of over the top roll 27a. In this instance, the yarn passes beneath the bottom roll 30a and then half-way around the roll 30a and then upwardly and rearwardly of the top roll 27a and partially around the same after which the yarn extends downwardly in engagement with the loop portion 65a of the yarn guide 63a and thus to the spool S in the manner heretofore described for the original form of the invention.

Thus, the second form of stop motion device differs from the original form in that the shank 62a of the yarn guide 63a is bent forwardly, as at 95, to thus cause the loop portion 65a of the yarn guide 63a to extend in a substantially horizontal plane outwardly of the bottom roll 30a and to thus position this loop portion 65a a substantial distance outwardly of the vertical plane of the front surface of the roll lifter support 57a.

The yarn, in its course from the top roll 27a to the spool, then extends over the outer surface of the loop portion 65a of the yarn guide 63a and thereby urges the roll lifter support 57a in a counter-clockwise direction in Figure 9 provided that there is sufficient tension in the yarn Y—a. The form of the invention shown in Figures 8, 9 and 10 operates in the identical manner which the original form of the invention operates and, therefore, a description thereof is deemed unnecessary. In this form of the invention, the yarn Y—a cannot pass between the top roll lifting member 50a and the rolls 27a and 30a as it traverses the rolls lengthwise thereof. Therefore, the loop portion 65a extends outwardly to one side only of the shank 62a. The yarn guide 63a also differs from the yarn guide 63 in that opposed ends of the elongated loop portion 65a are curved outwardly at 96 to thereby prevent the yarn Y—a from sliding off the ends of the loop portion 65a of the yarn guide 63a.

It is evident that the loop portion 65a may be omitted from the yarn guide 63a and in which instance, the yarn guide 63a would merely be L-shaped to provide a transverse portion, in lieu of the portion 65a, over and in engagement with which the yarn Y—a passes. Since the yarn cannot pass between the top roll lifting member 50a and the rolls 27a and 30a, it may be desirable to

provide a pair of the stop motion devices for each top roll, the devices then being spaced from each other and having a common yarn guide extending therebetween to thereby insure that the top roll 5 will be properly balanced. This being an obvious expedient, a detailed description and illustration thereof is deemed unnecessary.

Third form of twister stop motion device

10 In Figure 11, there is shown a third form of stop motion device which is substantially the same as the original form of the invention. However, the stop motion devices heretofore described have been described in association with a top roll of larger diameter than the bottom roll. The form of the invention shown in Figure 11 is particularly adapted to be used with a top roll of smaller diameter than the bottom roll. Since the parts and manner of operation thereof are associated with the form of the invention shown in Figure 11 are substantially the same as those shown in the original form of the invention, a detailed description thereof is deemed unnecessary and the parts shown in Figure 11 shall bear the same reference characters as those applied to like parts associated with the original form of the invention with the letter "b" affixed thereto.

20 The only difference between the form of the invention shown in Figure 11 and the original form shown in Figures 1 to 7, inclusive, is the shape of the top roll lifting member or roll separating member 50b. In the original form of the invention, the length and degree of arc of each of the surfaces 51 and 52 is substantially the same.

25 It will be observed in Figure 11 that the upper arcuate surface 51b is of substantially less radius than the lower arcuate surface 52b, the radii of the surfaces 51b and 52b conforming substantially to the radii of the top and bottom rolls 27b and 30b so the surfaces 51b and 52b are engaged for substantially their full lengths by the top and bottom rolls 27b and 30b respectively, when the top roll lifting member 50b is in the fully operative position shown in dotted lines in Figure 11.

30 When the top roll lifting member 50b is in the dotted line position, it is evident that the top roll 27b is elevated to the dotted line position shown. It is evident that, since the upper arcuate surface 51b is of a substantially less radius than the lower arcuate surface 52b, this surface 51b terminates a substantial distance short of the rear or outer end of the top roll lifting member 50b while, in the original form of the invention, the arcuate surface 51 extends from the rear end of the top roll lifting member 50 to a point immediately adjacent the front end thereof.

35 In order to accommodate the increased diameter of the bottom roll 30b, as shown in Figure 11, it is evident that the shank 62b of the yarn guide 63b is substantially longer than the shank 62 of the yarn guide 63 shown in Figure 5 so the yarn Y need not necessarily extend upwardly as it leaves the bottom surface of the bottom roll 30b. The shank 62b may be of the same length as the shank 62 if so desired.

40 It is thus seen that we have provided an improved stop motion for twisters which may be moved manually into a fully inoperative position when so desired even though the yarn may become parted and which may also be moved into a semi-operative position, in which instance the free or rear end of the wedge-shaped top roll lifting member is disposed closely adjacent the bite of the top and bottom rolls 27 and 30 with

11

means responsive to the yarn being parted or becoming unduly slack between the bite of the rolls and the spool on which the yarn is being wound for moving the top roll lifting member inwardly to be engaged by the rolls and thus pulled further inwardly to elevate the top roll out of engagement with the bottom roll and to thereby cause cessation of rotation of the top roll although the bottom roll may continue to rotate.

In the drawings and specification, there has been set forth a preferred embodiment of the invention and although specific terms are employed, they are used in a generic and descriptive sense only and not for purposes of limitation, the scope of the invention being defined in the claims.

We claim:

1. An improved stop motion for a twisting machine or the like for processing yarn, said twisting machine having at least one driven bottom roll and at least one top roll resting upon the bottom roll and being driven through contact with the bottom roll, said machine also having means onto which the yarn is directed from the rolls and being disposed below the rolls and said machine also having means for maintaining tension in the yarn, said stop motion comprising a horizontally disposed shaft disposed forwardly of the bottom roll and in substantially parallel relation to the axis of said bottom roll and also being disposed in substantially the same horizontal plane as the axis of said bottom roll, a roll lifter support oscillatably mounted on said shaft and having an upwardly extending arm thereon, means normally urging said upwardly extending arm towards the bite of the top and bottom rolls, a top roll lifting member pivotally mounted on said arm and extending towards and normally terminating closely adjacent the bite of the top and bottom rolls, said top roll lifting member having a relatively sharp edge remote from said arm and being provided with upper and lower outwardly diverging arcuate surfaces thereon, a yarn guide extending from the roll lifter support and being disposed beneath said shaft and through which the yarn extends in its course from the rolls to the means onto which the yarn is directed, the tension in the yarn normally holding the top roll lifting member out of engagement with the rolls, and the proximate surfaces of said top and bottom rolls rotating in a direction away from the top roll lifting member whereby, upon said yarn being parted at a point between the rolls and the means onto which the yarn is directed, the relatively sharp edge of the top roll lifting member will move towards and into engagement with the proximate surfaces of the top and bottom rolls thereby being pulled further into position between the top and bottom rolls to lift the top roll out of engagement with the bottom roll to thereby prevent further rotation of the top roll.

2. An improved stop motion for a twisting machine or the like for processing yarn, said twisting machine having at least one driven bottom roll and at least one top roll resting upon the bottom roll and being driven through contact with the bottom roll, said machine also having means onto which the yarn is directed from the rolls and being disposed below the rolls, and said machine also having means for maintaining tension in the yarn, said stop motion comprising a horizontally disposed shaft disposed forwardly of the bottom roll and in substantially parallel relation to the axis of said bottom roll and also

12

being disposed in a lower horizontal plane than the bite of said top and bottom rolls, a roll lifter support pivotally mounted on said shaft and having an upwardly extending arm thereon, means normally urging said upwardly extending arm towards the bite of the top and bottom rolls, a top roll lifting member pivotally mounted on said arm and extending towards and normally terminating closely adjacent the bite of the top and bottom rolls, said top roll lifting member having a relatively sharp edge remote from said arm, a yarn guide extending from the roll lifter support and disposed beneath said shaft and through which the yarn extends in its course from the rolls to the means onto which the yarn is directed, the tension in the yarn normally holding the top roll lifting member out of engagement with the rolls, the proximate surfaces of said top and bottom rolls rotating in a direction away from the top roll lifting member whereby, upon said yarn being parted at a point between the rolls and the means onto which the yarn is directed, the relatively sharp edge of the top roll lifting member will move towards and into engagement with the proximate surfaces of the top and bottom rolls thereby being pulled further into position between the top and bottom rolls to lift the top roll out of engagement with the bottom roll to thereby prevent further rotation of the top roll.

3. In a structure according to claim 2, means for limiting movement of the arm of the roll lifter support toward the bite of said top and bottom rolls to normally cause the top roll lifting member to assume a semi-operative position closely adjacent the bite of the top and bottom rolls, means operable manually for rotating the roll lifter support so the arm thereof is moved away from the bite of the top and bottom rolls, and means for locking said roll lifter support in the latter position whereby, although the yarn may be parted, the top roll lifting member will not move inwardly towards the bite of the rolls sufficiently to engage said rolls.

4. An improved stop motion for a twisting machine or the like for processing yarn, said twisting machine having at least one driven bottom roll and at least one top roll resting upon the bottom roll and being driven through contact with the bottom roll, said machine also having means onto which the yarn is directed from the rolls and being disposed below the rolls, and said machine also having means for maintaining tension in the yarn, said stop motion comprising a horizontally disposed shaft disposed forwardly of the bottom roll and in substantially parallel relation to the axis of said bottom roll and also being disposed in a lower horizontal plane than the bite of said top and bottom rolls, a roll lifter support pivotally mounted on said shaft and having an upwardly extending arm thereon, means normally urging said upwardly extending arm towards the bite of the top and bottom rolls, a top roll lifting member pivotally mounted on said arm and extending towards and normally terminating closely adjacent the bite of the top and bottom rolls, said top roll lifting member having a relatively sharp edge remote from said arm, a yarn guide extending from the roll lifter support and disposed beneath said shaft and through which the yarn extends in its course from the rolls to the means onto which the yarn is directed, the tension in the yarn normally holding the top roll lifting member out of engagement with the rolls, the proximate surfaces of

said top and bottom rolls rotating in a direction away from the top roll lifting member whereby, upon said yarn being parted at a point between the rolls and the means onto which the yarn is directed, the relatively sharp edge of the top roll lifting member will move towards and into engagement with the proximate surfaces of the top and bottom rolls thereby being pulled further into position between the top and bottom rolls to lift the top roll out of engagement with the bottom roll to thereby prevent further rotation of the top roll, traverse limiting means on said shaft for limiting the arc of movement of the top roll lifter support to thereby cause the relatively sharp edge of the top roll lifting member to remain closely adjacent the bite of the top and bottom rolls while the yarn is passing through the yarn guide under tension and to also limit movement of the top roll lifting member upon said top roll lifting member being pulled between the top and bottom rolls through engagement therewith upon the yarn being parted.

5. In a yarn processing machine, such as twist-
ers and the like, having at least one driven bot-
tom roll and at least one top roll resting upon the
bottom roll and being rotated through contact
with the bottom roll and take-up means for the
yarn disposed beneath said rolls and wherein the
yarn passes between the rolls and thence to the
take-up means under tension, an improved stop
motion for the top roll comprising a substantially
triangularly-shaped top roll lifting member dis-
posed adjacent the bite of said rolls, the prox-
imate surfaces of said rolls rotating in a direction
away from said lifting member, a support dis-
posed in a lower horizontal plane than said lift-
ing member and having an upwardly extending
arm thereon to which the lifting member is piv-
otally connected, means pivotally supporting the
support in said lower horizontal plane, means en-
gageable by the yarn under tension in its course
from the rolls to the take-up means for normally
holding the support and the top roll lifting mem-

ber in a semi-operative position wherein one edge
of the substantially triangularly-shaped top roll
lifting member is disposed closely adjacent the
bite of the top and bottom rolls, means operable
5 automatically upon the yarn being parted be-
tween the rolls and the take-up means for mov-
ing the corresponding edge of the top roll lift-
ing member into engagement with the rolls at the
bite thereof, whereupon the rolls will pull the
10 top roll lifting member inwardly between the
bite of said rolls to thereby lift the top roll out
of engagement with the bottom roll to cause ces-
sation of rotation thereof, means operable man-
ually for rotating the support so the arm there-
15 of is moved away from the bite of the top and
bottom rolls, means for locking said support in
the latter position whereby, although the yarn
may be parted, the top roll lifting member will
not move inwardly toward the bite of the rolls
20 sufficiently to engage said rolls, means for lock-
ing said support in said semi-operative position
and means on said support for permitting piv-
otal movement thereof while in a semi-operative
position to permit the same to pivot towards said
25 rolls upon the yarn being parted.
